SEAT LIFTER FOR TOILET BOWLS

Halbert L. White, Kansas City, Mo.

Application July 1, 1939, Serial No. 282,384

10 Claims. (Cl. 4—251)

My invention relates to improvements in seat lifters for toilet bowls.

One of the objects of my invention is the provision of novel mechanism for lifting the seat of a toilet bowl of the type having a foot depressed lever for effecting such lifting.

Another object of my invention is the provision of novel means for supporting the lever, carried wholly by the toilet bowl.

10. A further object of my invention is the provision of novel seat lifting means by which the lever when depressed will lift the seat to an open inclined position, and which permits the seat to be lifted by hand to a fully open position unsupported by the lever.

Another object of my invention is the provision of novel buffer means which yieldingly resists the downward movement of the seat to prevent slamming of the seat.

20. Still another object of my invention is the provision of a novel seat lifting mechanism, which is simple, cheap to make and easily and quickly installed without having to make any floor attachments, and which is easily operated and efficient in its operation.

The novel features of my invention are hereinafter fully described and claimed.

In the accompanying drawing, which illustrates my invention,

30. Fig. 1 is a side elevation showing my improved seat lifting mechanism operatively applied to a toilet bowl, the parts being shown in solid lines with the seat lowered, part of the lid being broken away. In dotted lines the parts are shown in the positions occupied by them when the seat is lifted to an inclined position, as shown in dotted lines, part of the seat being broken away.

Fig. 2 is a view similar to Fig. 1, the parts being shown in the positions occupied by them when 40 the seat has been lifted by hand to the fully open position and inclining rearwardly.

Fig. 3 is a plan view of what is shown in Fig. 1 in solid lines.

Fig. 4 is an enlarged side elevation of the buffer 45 member and a lower part of the link.

Fig. 5 is an enlarged vertical sectional view of the buffer member, the lower portion of the link, and parts connected to the buffer member, partly in section and partly in elevation.

50. Fig. 6 is a view partly in elevation and partly in section of the lever supporting member.

Fig. 7 is a view, partly in elevation and partly in section of a modified form of the lever supporting member, shown attached to the bowl, and 55 a portion of the lever.

Fig. 8 is an enlarged perspective of the lever supporting member shown in Fig. 7.

Similar characters of reference designate similar parts in the different views.

1 designates an ordinary toilet bowl, 2 the seat 5 hinged thereto, and 3 the lid also hinged to the bowl.

4 designates a vertical lever supporting member having at its upper end a hook 5 adapted to fit over the upper edge of the bowl 1, and provided 10 with a set screw 6 adapted to bear against the outer side of the bowl, to hold the member 4 from disengagement accidentally from the bowl. The lower end portion of the member 4 is bifurcated and its arms respectively provided with two 15 slots 7.

8 is a forwardly and rearwardly extending lever at one side of the bowl 1, and having extending through it and carried by it a transverse pivot pin 9, the ends of which are respectively slidable 20 in the slots 7.

The lever 8 is designed to have its forward end depressed by the foot, and at its rear end it is pivoted by a pin 10 to the lower end portion of an upwardly and downwardly 25 extending link 11, the upper end of which is pivoted by a pin 12 to one arm of a right angled bracket 13, the other arm of which is fastened to the under side of the seat 2 adjacent to the rear end thereof. 30

When the seat 2 is lowered, as shown in solid lines in Fig. 1, the pin 9 rests on the supporting member 4 at the lower ends of the slots 7.

When the front end of the lever is depressed, the link 11 will be forced upwardly to an extent 35 that the seat 2 will be lifted to the open inclined position, shown in dotted lines in Fig. 1.

If it is desired to lift the seat by hand to the fully open position, shown in Fig. 2, the slots 7 permit the pin 9 to slide upwardly in the slots to 40 the position shown in Fig. 2.

To prevent the seat 2 from slamming, when lowered, resilient resisting means are provided comprising the following described parts. The lower end of the link 11 is cylindrical and has 45 slidably fitted on it a tubular buffer member 14 having in its opposite walls two vertical slots 15 in which are respectively slidable the ends of a pin 16 which is tightly fitted in a transverse hole in the link 11. The lower end of the buffer member 14 has fastened in it a disk 17 against the upper side of which bears the lower end of a coil spring 18, the upper end of which bears against the lower end of the link 11. A soft rubber button 19 is mounted on the lower end of the 50 55

buffer member 14, and is adapted to strike the floor, when the seat 2 is lowered and with it the link 11.

In operation, the foot depresses the front end 5 of the lever 8, thus through the link 11 and bracket 13 lifting the seat 2 to the inclined position, shown in Fig. 1 in dotted lines. Upon withdrawing or lessening the foot pressure, the seat 2 lowers by gravity, and before it strikes the bowl 1, 10 the buffer member button 19 strikes the floor, thereby resisting the downward movement of the link 11 due to the latter compressing the spring 18, and the link 11 will hold the seat from slamming against the bowl.

15 If it is desired to lift the seat by hand to the fully open position, the pin 9 sliding in the slots 7 permits of such movement.

In the modification, shown in Figs. 7 and 8, the support for the lever 8 comprises a right angled member one horizontal arm 20 of which rests on the flange 21 at the lower part of the bowl 1, and a bolt 22, which is employed to fasten the bowl to the floor, is extended through a hole 23 in said arm, and fastens the latter tightly to the upper side of the flange 21. The other arm 24 of the right angled lever supporting member is bifurcated and its arms are provided respectively with slots 25 in which are respectively slidably fitted the ends of the pivot pin 9.

30 In operation, the supporting member 20—24, pivotally supports the lever 8 in the same manner as does the member 4 of the form shown in Fig. 1.

35 By supporting the lever on a member wholly carried by the bowl 1, as is the case in both forms of my invention, no floor attachment are required, and the device may be mounted easily in operative condition on the bowl by an unskilled person.

Other modifications of my invention, within 40 the scope of the appended claims, may be made without departing from the spirit of my invention.

What I claim is:

1. In combination with a toilet bowl, a hinged seat therefor, a lever, and means actuated by said 45 lever for lifting said seat, of a member having a hook engaging and supported by the upper end of said bowl and alone supporting said member, and means pivotally engaging said lever with said member.

50 2. In combination, a toilet bowl, a hinged seat therefor, a lever, and means actuated by said lever for lifting said seat, of a member supported by said bowl, and means pivotally and slidably engaging said lever with said member for permitting sliding of said lever within predetermined limits with respect to said member.

3. In combination, a toilet bowl, a hinged seat therefor, a lever, and means actuated by said lever for lifting said seat, of a member having a hook 60 engaging and supported by the upper end of said bowl and alone supporting said member said member having a slot, and a pivot pin carried by said lever and slidably in said slot and supported by said member when at one end of said slot.

65 4. In combination, a toilet bowl, a hinged seat therefor, a lever, and means pivotally supporting said lever, of a link pivoted to said seat and to said lever, for lifting the seat when the lever is

swung in one direction, a buffer member slidable on said link and adapted to strike the floor when said seat is lowered, and resilient means carried by said link for resisting the downward movement of said link when said buffer member strikes the 5 floor.

5. In combination, a toilet bowl, a hinged seat therefor, a lever, and a link pivoted to said seat and to said lever, of means supported by said bowl for pivotally supporting said lever, and resilient means carried by said link and adapted to strike the floor when said seat is lowered for resisting downward movement of said seat.

6. In combination, a toilet bowl, a hinged seat therefor, a lever, and a link pivoted to said 15 seat and to said lever, of a member having a hook engaging and supported by the upper edge of said bowl and alone supporting said member, and to which member said lever is pivoted, and resilient means carried by said link and adapted to strike 20 the floor when said seat is lowered for resisting downward movement of said seat.

7. In combination, a toilet bowl, a hinged seat therefor, a lever, and a link pivoted to said seat and to said lever, of a member having a hook en- 25 engaging and supported by the upper edge of said bowl said member having a longitudinal slot, a pin carried by said lever and slidably in said slot and supported by said member when at one end of said slot, and resilient means carried by said link 30 and adapted to strike the floor for resisting downward movement of said seat.

8. In combination, a toilet bowl, a hinged seat therefor, a lever, and a link pivoted to said seat and to said lever, of a member having a hook en- 35 engaging and supported by the upper edge of said seat and alone supporting said member, said member being pivoted to said lever, a buffer member slidable on said link and adapted to strike the floor when said seat is lowered, and a spring 40 bearing against said link and said buffer member, and which is compressed when said buffer member strikes the floor.

9. In combination, a toilet bowl, a hinged seat therefor, a lever, and means actuated by said 45 lever for lifting said seat, of a member supported by said bowl and having a vertical slot, and a pivot pin carried by said lever and slidably in said slot and when said seat is lowered resting on said member at the lower end of said slot, said actuating means, when said lever is depressed to its lowest position lifting said seat to an inclined open position, said pin being movable upwardly in said slot, should said seat be raised by hand above said inclined position.

10. In combination, a toilet bowl, a hinged seat therefor, a lever, and means actuated by said lever for lifting said seat only to an open inclined position, of a member having a hook engaging and supported by the upper edge of said bowl and 60 alone supporting said member said member having a vertical slot, and a pin carried by said lever and slidably in said slot and resting on said member in the lower end of said slot when said seat is lowered, and being movable upwardly in said 65 slot should said seat be raised by hand above said inclined position.

HALBERT L. WHITE.
